CLOSURE CONTROLLED LIGHT

Michael A. Okoneski, Holland, Ohio, assignor of
one-half to Sadie Czerniak, Toledo, Ohio

Application April 21, 1942, Serial No. 439,890

1 Claim. (Cl. 200—54)

This invention relates to new and useful improvements in closure controlled lights, involving a closure operated switch, especially adapted for automatically lighting the interior of coal bins, closets and other enclosures, when a closure thereto is opened.

The principal object of the present invention is to provide a closure operated switch structure for controlling a light automatically upon operation of the complementary door or other closure.

Other objects and advantages of the invention will become apparent to the reader of the following description.

In the drawings—

Figure 1 represents a fragmentary outside elevational view showing a closure and the approximate location of the switch means.

Figure 2 is a fragmentary vertical sectional view taken substantially on the line 2—2 of Figure 1.

Figure 3 is a vertical sectional view through the switch structure.

Figure 4 is a horizontal sectional view taken substantially on the line 4—4 of Figure 3.

Figure 5 is a transverse vertical sectional view taken substantially on the line 5—5 of Figure 3.

Referring to the drawings wherein like numerals designate like parts, it can be seen in Figure 1 that numeral 5 denotes a door frame which includes vertical side members 6 and a horizontal top member 7.

Numeral 8 generally refers to the switch which makes up the present invention. This switch structure 8 includes a plate 9 which goes against the underside of the top member 7 of the door frame 5. The switch further includes a box 10 open at its top and provided with a side flange 11. The side flange 11 and the plate 9 have registering openings 12 through which screws or other securing elements 13 can be disposed for securing the switch in place as shown in Figure 2. It is preferable that the box 10 have open sides so that the parts can be readily reached for repairs and replacement.

The bottom of the box 10 has a guide rib 14 extending longitudinally thereof which is straddled by the lower bifurcated end of a slide plate

15, the upper end of which has a plunger 16 projecting therefrom and through a bushing of insulation in a plate 17 and also through an opening in one edge of the box 10.

5 As can be seen in Figure 3, this plunger 16 actually projects from a plate 18 of insulation carried by the plate 15.

The plates 17 and 18 of insulation have contacts 19, 20 thereon to which connect conductor 10 wires 21, 22, respectively.

The plate 15 with its contact 20 is urged into position with the contact 20 engaging the contact 19 by a compression spring 23 interposed between the plate 15 and the back wall of the box 10.

15 It can now be seen, that the plunger 16 will normally bear against a complementary door 25, with the contacts 19, 20 in spaced relation, and the spring 23 under compression.

20 When the door 25 is open, the plunger 16 is released and the effect of the spring 23 will force the plate 15 to the left in Figure 3 until the contact 20 engages the contact 19, closing a circuit including the conductors 21, 22 and a 25 light and source of current (not shown), thus energizing the light and illuminating the enclosure.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

35 In combination with a closure, a switch, said switch including a box, a plate of insulation in the box, a contact on the plate of insulation, a slide structure having one end bifurcated, a guide rib in the box and which the bifurcated end of the slide structure straddles, a plunger projecting from the slide structure to the exterior of the box, and a compression spring in the box for normally urging the slide structure and plunger toward the closure, said structure including a plate of insulation and a contact thereon in the path of the first-mentioned contact.

MICHAEL A. OKONESKI.
